UNITED STATES PATENT OFFICE.

GEORGE CUTTER, OF SOUTH BEND, INDIANA.

LOCKING DEVICE FOR ARC-LAMP HANGERS.

No. 839,367.

Specification of Letters Patent.

Patented Dec. 25, 1906.

Application filed June 30, 1906. Serial No. 324,273.

To all whom it may concern:

Be it known that I, GEORGE CUTTER, a citizen of the United States, residing at South Bend, in the county of St. Joseph and State of Indiana, have invented new and useful Improvements in Locking Devices for Arc-Lamp Hangers, of which the following is a specification.

This invention relates to locking devices for electric-arc-lamp hangers.

Arc-lamp hangers have in some instances been constructed of a stationary part carrying contacts and a movable part carrying contacts adapted to be thrown into and out of engagement with the contacts on the stationary part. The movable part carries the lamp and is drawn to or separated from the stationary part by means of a cable which extends to a position from which a workman may control the position of the lamp to clean the same or renew the carbons. It is customary in these hangers to provide a locking device to hold the movable part against movement independently of the controlling-cable, so that the weight of the lamp will not be upon the cable when the lamp is elevated.

An object of my invention is to provide an improved locking device which locks and unlocks upon alternate pulls upon the controlling-cable.

Other and further objects will appear in the following description and will be more particularly pointed out in the appended claims.

In the drawings, Figure 1 is a side elevation of the stationary and the movable parts coupled together, all parts of the hanger not bearing upon my invention not being shown. Fig. 2 is a like view showing the movable part lowered. Fig. 3 is a detail inside view of one of the locking devices in locking position, the slot and the projection on the movable member being shown in dotted lines. Fig. 4 is a view similar to Fig. 3, showing the effect of an upward pull upon the controlling-rope when the device is in locking position. Fig. 5 is a view similar to Figs. 3 and 4, showing the first effect produced by releasing the rope after the parts are in the position shown in Fig. 4. Fig. 6 is a view similar to Figs. 3, 4, and 5, showing the final effect produced by releasing the controlling-rope; and Figs. 7, 8, and 9 show three positions of a locking device and a projection upon the second upward pull on the controlling-cable.

Referring more particularly to the draw-

ings, 1 designates a depending stationary part in the form of a tube provided with vertical guide-slots 2 upon opposite sides, said slots opening at their ends at the bottom of the tube into enlarged inverted-V-shaped recesses 2^a.

3 indicates the movable member, having a pointed end 4 and suspended by a cable 5, which extends through the stationary member in the usual manner. The movable member has projecting from opposite sides a pair of projections 6, carried by a collar 7, freely turning on the movable member.

The projections on the movable member are adapted to be engaged by a pair of locking devices, one for each projection. As these locking devices are duplicates of each other, it will be necessary to describe only one of them. Each locking device comprises a plate or member 8, pivoted at its upper end upon a bolt 9, which serves as the pivot for both devices. The pivot 9 is to one side of the slot 2, near the upper end thereof, and the plate normally extends obliquely across the slot, being held in this position by a bar 10. This bar 10 is held elevated above the plate 8 by bosses 10^a, and a shoulder 11 on the plate engages the bar when the plate is in its lower and normal position. The plate carries a holding or supporting dog or member 12 of bell-crank formation and a locking and releasing dog or trip 13, both of which are pivotally mounted intermediate of their ends and are held in their several positions by leaf-springs 14, which frictionally bear against the sides of said dogs.

In locking position, as shown in Fig. 3, the pivoted plate lies obliquely across the slot 2, and the dog 12 supports one of the projections 6, said dog being held in supporting position by a lug 15 on the plate and one end 16 of the trip 13. To release the supporting-dog 12, the cable 5 is pulled, thus elevating the projection 6 until it engages the face 17 of the trip and moves the end 16 of the latter out of the path of the arm 18 of the dog 12. The cable 5 is now slackened and the weight of the lamp causes the projection 6 to swing the dog 12 on its pivot, and thus permit said projection to be freed and to move downwardly in a slot 2. In swinging on its pivot a shoulder 19 on the dog 12 engages the lug 15 on the plate 8 and causes the plate to swing slightly on its pivot 9. After the projection 6 has passed below the dog the plate swings to its normal position, causing the dog 12 to lie

across the slot. To elevate the lamp, the cable 5 is again pulled and the projection 6, engaging one arm of the dog, suddenly moves the same to holding position and then rides 5 on the underface 20 of the arm until it reaches the end of the arm. While the projection 6 is riding or sliding on the arm of the dog 12 the plate 8 swings on its pivot 9, and when the end of the arm is reached the projection 6 10 passes into engagement with the end 21 of the trip 13, causing the end 16 of said trip to pass in front of the dog 12 and lock the same against swinging. The cable is again slackened and as the projection 6 lowers in the 15 slot it passes onto the supporting-dog, the plate 8 swinging under the action of gravity to place the dog again in proper locking position. To strengthen the stationary member, which is weakened by the vertical slots 20 on opposite sides, I provide bars 22, each of which connects a lower boss 10' on one side of each slot with a boss 23 on the opposite side of the same slot.

Having thus described my invention, what 25 I claim, and desire to secure by Letters Patent, is—

1. The combination with a stationary part and a movable part, of a projection carried by one of said parts, a holding-dog carried by the 30 other part, and a trip to lock the holding-dog against movement pivoted intermediate its ends to the latter part, engaged one side of its pivot by the projection to release the holding-dog and engaged by the projection 35 on the other side of its pivot to lock the holding-dog.

2. The combination with a stationary part and a movable part, of a projection carried by one of said parts, a pivoted dog of bell-crank 40 formation carried by the other part, and a trip pivoted intermediate its ends for holding the dog against movement and engaged alternately on opposite sides of its pivot by the projection to alternately release and lock the 45 dog.

3. The combination of a tubular, stationary part provided with vertical slots on opposite sides and enlarged, inverted-V-shaped recesses at the lower ends of the slots; a movable 50 part carrying a collar adapted to turn thereon and provided with projections on opposite sides to work in the slots; and locking devices carried by the stationary part and constructed to engage the projections.

55 4. The combination with the stationary part provided with a vertical guide, of a movable part provided with a projection, and a locking device comprising a swinging plate normally lying across the guide, a holding-dog 60 carried by the plate, and a locking and releasing trip for the dog carried by the plate and controllable by said projection.

5. The combination with the tubular stationary part provided with a vertical slot; of 65 a locking device comprising a movable plate

normally lying across the slot, a holding-dog on said plate, and a locking and releasing trip for the dog; and a movable part working in the stationary part and carrying a projection movable in the slot and controlling the 70 position of the trip.

6. The combination with a stationary part provided with a vertical guide; of a movable part carrying a projection; and a locking device carried by the stationary part comprising 75 a movable part normally lying across the guide, a pivoted dog of a bell-crank formation carried by the movable part of the locking device, and a trip pivoted intermediate its ends and controlled by the projection. 80

7. The combination with a tubular stationary member provided with a vertical slot; of a movable rope-controlled member; and a locking device carried by the stationary member and comprising a pivoted plate, a 85 pivoted holding-dog of bell-crank formation mounted on the plate, and a trip pivoted intermediate its ends to the plate and controlled by the projection.

8. The combination with a tubular stationary member provided with vertical slots 90 on opposite sides, of a movable member carrying projections on opposite sides, a pair of pivoted plates one lying obliquely across each slot and provided with a shoulder, a 95 pair of bars each engaging a shoulder of each plate to limit the swinging of the plate in one direction, a pair of holding-dogs each pivoted to a plate, a pair of leaf-springs each frictionally engaging a dog, a pair of trips each controlled by a projection for locking and releasing a dog, and a pair of leaf-springs each frictionally engaging a trip. 100

9. The combination with a stationary member and a movable part, of a projection 105 carried by one of said parts, a pivoted holding-dog carried by the other part, and engaged by the projection on opposite sides of its pivot to be moved to and from its holding position, and a trip pivoted intermediate its 110 end, locking the holding-dog against movement in one position, and engaged on opposite sides of its pivot to lock and to release the holding-dog.

10. The combination with a stationary 115 part and a movable part, of a projection carried by one of said parts, and a locking device carried by the other part and comprising a movable member, a holding-dog carried by the movable member, a trip to lock the holding-dog against movement, pivoted intermediate of its ends to the movable plate, engaged on one side of its pivot by the projection to release the holding-dog, and engaged on the other side of its pivot by the projection to lock the holding-dog. 120

11. The combination with a stationary part and a movable part, of a projection carried by one of said parts, a locking device carried by the other of said parts and compris- 130

ing a movable member, a holding-dog carried by said member, and a trip to lock the holding-dog against movement, moved into and out of engagement with the dog by being 5 engaged by the projection.

12. The combination with a stationary part and a movable part, of a projection carried by one of said parts, and a locking device carried by the other of said parts and 10 comprising a movable member, a dog of bell-crank formation pivoted to said member,

and a trip for holding the dog against movement pivoted intermediate of its ends and engaged alternately on opposite sides of its pivot by the projection to alternately release 15 and lock the dog.

In testimony whereof I affix my signature in presence of two subscribing witnesses.

GEORGE CUTTER.
